United States Patent Office

Des. 184,754
Patented Mar. 31, 1959

184,754

COMBINED PLATTER AND HOLDER THEREFOR

James J. Melich and Edwin G. Melich, Chicago, Ill.

Application September 15, 1958, Serial No. 52,629

Term of patent 14 years

(Cl. D44—10)

Fig. 1 is a top plan view of a combined platter and holder therefor, showing our design;

Fig. 2 is a bottom plan view;

Fig. 3 is a side elevational view in partial section; and
Fig. 4 is an end elevational view.

We claim:

The ornamental design for a combined platter and holder therefor, as shown.
